BEST AVAILABLE COPY

July 12, 1915.

SPECIFICATION

49

A careful search has been made this day for the original file or a printed copy of the same, for the purpose of reproducing the said specification to form a part of this book, but at this time nothing can be found from which a reproduction or printed copy can be made.

Finis D. Morris,

Chief of Division E.

AWK

Pat. No. 49

The records of the office show that the spec. for this patent has not been printed.
